UNITED STATES PATENT OFFICE

JAMES A. CAMERON, OF BROOKLYN, NEW YORK, ASSIGNOR TO CAMERON MACHINE COMPANY, OF BROOKLYN, NEW YORK, A CORPORATION OF NEW YORK

FRICTION RESISTANCE DEVICE FOR WINDING MACHINES

Application filed October 25, 1928. Serial No. 314,860.

This invention relates to winding machines for webs of flexible material, and has for its main object the production of means whereby coils of flexible material may be so wound as to have such different characteristics of hardness as may be desired under different conditions or with different materials.

In an application filed July 28, 1926, Ser. No. 125,350, now Patent No. 1,707,047, is disclosed a winding machine in which the rise of a member, displaceable by the accumulation of wound material, is opposed at a diminishing rate by certain instrumentalities of which two examples, one a counterweighting means and the other a friction means associated with a carriage and guides, are shown. The present application is a continuation in part of the previously-mentioned application in that it is directed specifically to the friction means associated with the carriage and guides.

In the accompanying drawings the invention is disclosed in several concrete and preferred forms in which:

Fig. 1 is a somewhat diagrammatic view in side elevation of a winding machine embodying the invention;

Fig. 2 is a view, partly in elevation and partly in section, looking in the direction of arrow 2 of Fig. 1;

Fig. 3 is a sectional view substantially on the plane of line 3—3 of Fig. 2;

Fig. 4 is a sectional view substantially on the plane of line 4—4 of Fig. 2;

Fig. 5 is a detail view similar to Fig. 2 but showing a modified form of the invention; and

Fig. 6 is a sectional view substantially on the plane of line 6—6 of Fig. 5.

The winding means may be of widely different types but as here exemplified by drums 1 and 2. The member displaceable by the accumulation of material may be either a winding shaft 3 or top pressure roll 4, but the invention is here exemplified by applying it to the top pressure roll. As here shown, the top pressure roll and its carriage 34 are carried by flexible connections 6 and counter-weighting means 7, the connections passing

here over sprocket wheels 8 and the counter-weighting means sliding on inclined ways 9. Carriage 34 slides on guides 35 of the framework, and associated with the guides and carriage are means to resist the movement of displacement of said carriage with respect to said guides. As here shown, these means take the form of taper surfaces and complementary resilient members. As shown in Figs. 2, 3 and 4, 36 are brackets carried by the guides, or the framework, and these brackets are provided with taper brake or retarding surfaces 37, the taper being here outward as the surfaces extend upward. These surfaces may extend any distance desired. Carried by carriage 34 are springs 38 to engage the brake surfaces, and it will be understood that the cooperation of the surfaces and springs retard or offer resistance to the displaceable member, here the top pressure roll, as it rises in response to an increase in the amount of wound material on the winding shaft. It will further be understood that the shape of surface 37 will determine the amount of resistance offered to the rise of the carriage, and that this can be varied by having differently shaped surfaces. In the present instance, the resistance decreases as the top pressure roll rises.

In Figs. 5 and 6 is shown a modification of this invention in that brake surfaces 37 are pivotally supported at 39 and are normally urged outward by springs 40, there being an adjustment screw 41 to adjust the amount of taper desired.

I claim:

1. In a winding machine, a member displaceable by accumulation of wound material, a carriage supporting said member and moving with it as it becomes displaced, guides on which the carriage slides, and means, including taper surfaces, to resist the movement of displacement of said carriage with respect to said guides.

2. In a winding machine, a member displaceable by accumulation of wound material, a carriage supporting said member and moving with it as it becomes displaced, guides on which the carriage slides, and means, including complementary taper surfaces and resili-

ent members, to resist the movement of displacement of said carriage with respect to said guides.

3. In a winding machine, a member displaceable by accumulation of wound material, a carriage supporting said member and moving with it as it becomes displaced, guides on which the carriage slides, and means, including taper surfaces, to resist, at a diminishing rate, the movement of displacement of said carriage with respect to said guides.

4. In a winding machine, a member displaceable by accumulation of wound material, a carriage supporting said member and moving with it as it becomes displaced, guides on which the carriage slides, and means, including complementary taper surfaces and resilient members, to resist, at a diminishing rate, the movement of displacement of said carriage with respect to said guides.

5. In a winding machine, a member displaceable by accumulation of wound material, a carriage supporting said member and moving with it as it becomes displaced, guides on which the carriage slides, flexible connections and counterweighting means to support the carriage, and means, including taper surfaces, to resist the movement of displacement of said carriage with respect to said guides.

30 6. In a winding machine, a member displaceable by accumulation of wound material, a carriage supporting said member and moving with it as it becomes displaced, guides on which the carriage slides, flexible connections and counterweighting means to support the carriage, and means, including complementary taper surfaces and resilient members, to resist the movement of displacement of said carriage with respect to said guides.

40 7. In a winding machine, a member displaceable by accumulation of wound material, a carriage supporting said member and moving with it as it becomes displaced, guides on which the carriage slides, flexible connections and counterweighting means to support the carriage, and means, including taper surfaces, to resist, at a diminishing rate, the movement of displacement of said carriage with respect to said guides.

50 8. In a winding machine, a member displaceable by accumulation of wound material, a carriage supporting said member and moving with it as it becomes displaced, guides on which the carriage slides, flexible connections and counterweighting means to support the carriage, and means, including complementary taper surfaces and resilient members, to resist, at a diminishing rate, the movement of displacement of said carriage with respect to said guides.

Signed at the city of New York, in the borough of Brooklyn, county of Kings, and State of New York, this 16 day of October, 1928.

JAMES A. CAMERON.
